WIRE CONNECTOR

Oscar F. Tallman, St. Louis, Mo., assignor to
 James R. Kearney Corporation, St. Louis, Mo.,
 a corporation of Missouri

Application June 8, 1940, Serial No. 339,578

9 Claims. (Cl. 24—123)

This invention relates generally to wire connectors of the type employed to mechanically attach telephone and other drop or service wires to houses, buildings, and other structures, and more specifically to a wire connector of the general type of the wire connector covered by United States Letters Patent No. 2,110,407, issued on March 8, 1938, the predominant object of the present invention being to provide a wire connector of the type that holds a drop or service wire in accordance with the snubbing principle, instead of through the use of clamping pressure applied to the insulation of the wire, and which is of such improved construction and arrangement that the operation of applying a wire thereto is simplified.

Wire connectors of the type covered by the United States Letters Patent referred to above have been widely distributed, and in use have performed their intended function in a highly efficient manner. However, in order to simplify, to some degree, the operation of applying a wire to a wire connector of the general type of the patented wire connector, the wire connector of the present invention was developed. The main points of difference between the wire connector of the present invention and the patented wire connector is that the spirally arranged snubbing portion of the device of the present invention is extended at an angle to the direction of extension of the wire being connected, instead of in alignment with such direction of extension of said wire as in the case of the patented wire connector. It has been found that when the spiral snubbing portion of wire connector is extended at an angle to the direction of extension of a wire being connected with the aid of the device, the operation of applying the wire to the snubbing portion of the wire connector is simplified. Also because of the changed arrangement of the snubbing portion of the device of the present invention, when compared with the structure of the patented wire connector, a different bail structure is employed which, because of its improved construction and arrangement, serves to aid in simplifying the operation of applying a wire to the wire connector disclosed herein.

Fig. 1 is a perspective of the improved wire connector disclosed herein, showing same as it appears when a wire is connected thereto.

Fig. 2 is a front elevation of the wire connector illustrated in Fig. 1, the wire associated therewith being shown in cross-section.

Fig. 3 is a perspective looking upwardly to-

ward the under side of the improved wire connector shown in Figs. 1 and 2, a portion of the bail being broken away.

Fig. 4 is a perspective similar to Fig. 3 but showing the complete bail in the displaced position it is caused to assume when a wire is being applied to the wire connector.

In the drawing, wherein is shown for the purpose of illustration, merely, one embodiment of the invention, A designates the improved wire connector generally. The wire connector A includes a wire-receiving portion 1 which is formed from a strip or length of metal, or other suitable material, of channel shaped cross-section. The wire-receiving portion 1 includes a straight portion 2 having an outwardly curved outer end portion 3 which eliminates likelihood that the insulation of a wire received by the portion 2 of the wire-receiving portion 1 of the device would be cut by the forward edge of said portion 2. The portion of the length of material from which the wire-receiving portion of the device A is formed, that extends from the portion 2, is bent in spiral formation to provide the wire-receiving portion 1 with a spiral snubbing portion 4, and it is important to note that the axis of this spiral snubbing portion is extended at an approximate right angle relative to the direction of extension of the portion 2 of the wire-receiving portion 1 and with respect to a wire received thereby. The length of material which provides the wire-receiving portion 1 of the device A is shaped to provide an outstanding arcuate flange 5 through which a pair of apertures 6 are formed, said flange being produced by parallel, outwardly extended, and contacting portions of the length of material which produces the wire-receiving portion of the device. At the end of the spiral snubbing portion 4 of the wire-receiving portion 1 of the wire connector A an integral tongue 7 is provided which, as shown in Fig. 2, is curved so that it partially embraces a wire associated with the wire connector.

The improved wire connector A includes also a bail 8 which is preferably made from a single length of wire bent double to provide a closed loop at one end. This closed loop of the bail is embraced and frictionally engaged by spiral wire element 9, resembling a coil spring, which serves as a wear member. Leg portions of the bail extend forwardly from the closed loop portion thereof and these leg portions are arranged in crossed over and under relation at a point immediately above the point where the straight portion 2 of the wire-receiving portion of the de-

vice merges into the spiral snubbing portion of said wire-receiving portion of the device. The forward end portions of the legs of the bail are bent downwardly as indicated at 10 in the drawing, and from the lower ends of the portions 10 of the legs of the bail, portions 11a and 11b are extended rearwardly in spaced relation to and in substantial parallelism with respect to upper forward portions of the legs of the bail. The rearwardly extended portions 11a and 11b of 10 the legs of the bail 8 are extended through the apertures 6 formed through the arcuate flange 5, and the portion 11b is provided with a laterally bent end portion 12 (Fig. 3) which prevents unintended displacement of said portion from 15 the aperture 6 through which it is extended.

When the improved wire connector A is to be applied to a wire W for the purpose of connecting the wire to a support, the rearwardly extended portion 11a of a leg of the bail 8 is freed from 20 the aperture 6 of the arcuate flange 5 through which it is extended, by moving the bail forwardly relative to the wire-receiving portion of the device and by manipulating the leg of the bail of which said portion 11a forms a part so as to 25 effect release of said portion 11a from its aperture. The bail is then turned over to one side of the wire-receiving portion of the device, the rearwardly extended portion 11b of the bail, which is prevented from being displaced from its 30 aperture 6 in the arcuate flange 5 by the bent end 12 thereof, serving as a pivot point about which the bail is turned, as shown in Fig. 4 and by dotted lines in Fig. 2. The wire W is then 35 drawn to the desired degree of tautness and a portion of the wire is laid in the straight portion 2 of the wire-receiving portion of the device, and the portion of the wire located rearwardly of said wire portion which is disposed in the straight portion 2 of the wire-receiving 40 portion 1 is wound spirally through the spiral snubbing portion 4 of the device, a portion of the wire being introduced behind the curved tongue 7 so as to be partially embraced thereby. The bail 8 is then turned back to its normal 45 position and the rearwardly extended leg portion 11a is re-introduced into its aperture in the arcuate flange 5. The closed loop at the rear end of the bail is then applied a hook H, or other element, secured to the support S to which 50 the wire is to be attached. The crossed portions of the legs of the bail 8, being positioned immediately above the portion of the wire W that passes from the portion 2 of the wire-receiving portion 1 to the snubbing portion 4 55 thereof, retains the wire in the channel of said wire-receiving portion. Also the tongue 7, because it partially embraces the wire as shown in Fig. 2, serves to aid in retaining the wire in 60 the channel of the wire-receiving portion 1 of the wire connector.

It is obvious that a wire attached to a support with the aid of the improved wire connector disclosed herein is very securely engaged by the wire connector by a snubbing action which 65 does not affect the insulation of the wire injuriously. Also it is obvious that whip and vibration of the wire is taken up by the loose connection between the wire connector A and the hook H, and, therefore, there is no centering of 70 wear due to such whip and vibration of the wire at the tie-in point of the wire. As a result of this situation, the life of the wire is greatly prolonged inasmuch as the wire is not held by the connector to the tensile strength of the insu- 75

lation, but to the breaking strength of the wire. I claim:

1. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound about an axis which is extended at an angle with respect to the direction of extension of said substantially straight portion, means extended from said wire-receiving portion at a point adjacent to said substantially straight portion thereof, and a bail normally connected to said means of the wire-receiving portion of the connector substantially in longitudinal alignment with respect to the substantially straight portion thereof, said bail being movable from its normal position with respect to said wire-receiving portion to a displacement position with relation thereto without complete detachment therefrom to permit application of a wire to the wire-receiving portion of the wire connector.

2. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound about an axis which is extended at an angle with respect to the direction of extension of said substantially straight portion, and a bail normally connected to the wire-receiving portion of the connector substantially in longitudinal alignment with respect to the substantially straight portion thereof, said bail being movable from its normal position with respect to said wire-receiving portion to a displaced position with relation thereto to permit application of a wire to the wire-receiving portion of the wire connector, and said bail including leg portions which are crossed at a point immediately above a portion of said wire-receiving portion to retain a wire in the channel thereof.

3. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound spirally about an axis which is extended at an angle with respect to the direction of extension of said substantially straight portion, a flange formed on said wire-receiving portion at a point adjacent to said substantially straight portion thereof, said flange having apertures formed therein, and a bail having legs provided with bent portions parts of which are extended through the apertures of said flange so as to normally connect said bail to said wire-receiving portion in substantial longitudinal alignment with respect to the substantially straight portion thereof.

4. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound spirally about an axis which is extended at an angle with respect to the direction of extension of said substantially straight portion, a flange formed on said wire-

receiving portion at a point adjacent to said substantially straight portion thereof, said flange having apertures formed therein, and a bail having legs provided with bent portions parts of which are extended through the apertures of said flange so as to normally connect said bail to said wire-receiving portion in substantial longitudinal alinement with respect to the substantially straight portion thereof, the part of the bent portion of one of the legs of the bail being removable from the aperture of the flange through which it extends to permit the bail to be rotated about the aperture-received part of the bent portion of the other bail leg to move the bail to a displaced position for application of a wire to the wire-receiving portion of the wire connector. 5 10 15

5. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound spirally about an axis which is extended at an angle with respect to the direction of extension of said substantially straight portion, a flange formed on said wire-receiving portion at a point adjacent to said substantially straight portion thereof, said flange having apertures formed therein, and a bail having legs provided with bent portions parts of which are extended through the apertures of said flange so as to normally connect said bail to said wire-receiving portion in substantial longitudinal alignment with respect to the substantially straight portion thereof, the part of the bent portion of one of the legs of the bail being removable from the aperture of the flange through which it extends to permit the bail to be rotated about the aperture-received part of the bent portion of the other bail leg to move the bail to a displaced position for application of a wire to the wire-receiving portion of the wire connector, and means for preventing removal of said aperture-received part of the bent portion of said other bail leg from the aperture of the flange by which it is received.

6. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound spirally about an axis which is extended at an angle with respect to the direction of extension of said substantially straight portion, a flange formed on said wire-receiving portion at a point adjacent to said substantially straight portion thereof, said flange having apertures formed therein, and a bail having legs provided with bent portions parts of which are extended through the apertures of said flange so as to normally connect said bail to said wire-receiving portion in substantial longitudinal alignment with respect to the substantially straight portion thereof, the part of the bent portion of one of the legs of the bail being removable from the aperture of the flange through which it extends to permit the bail to be rotated about the aperture-received part of the bent portion of the other bail leg to move the bail to a displaced position for application of a wire to the wire-receiving portion of the wire connector, and means comprising a bent end portion for preventing removal of said aperture-received part of the bent portion of said other 75

bail leg from the aperture of the flange by which it is received.

1. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound spirally about an axis which is extended at an angle with respect to the direction of extension of said substantially straight portion, a flange formed on said wire-receiving portion at a point adjacent to said substantially straight portion thereof, said flange having apertures formed therein, and a bail having legs provided with bent portions parts of which are extended through the apertures of said flange so as to normally connect said bail to said wire-receiving portion in substantial longitudinal alignment with respect to the substantially straight portion thereof, the part of the bent portion of one of the legs of the bail being removable from the aperture of the flange through which it extends to permit the bail to be rotated about the aperture-received part of the bent portion of the other bail leg to move the bail to a displaced position for application of a wire to the wire-receiving portion of the wire connector, said legs of said bail being crossed at a point immediately above a portion of said wire-receiving portion to retain a wire in the channel of said wire-receiving portion.

35 8. A wire connector comprising a wire-receiving portion of channel cross-sectional shape having a substantially straight portion disposed in longitudinal alignment with reference to the direction of extension of a wire connected by the wire connector, and provided with a spiral wire-snubbing portion wound spirally about an axis which is extended at an angle with respect to the direction of extension of said substantially straight portion, a flange formed on said wire-receiving portion at a point adjacent to said substantially straight portion thereof, said flange having apertures formed therein, and a bail having legs provided with bent portions parts of which are extended through the apertures of said flange so as to normally connect said bail to said wire-receiving portion in substantial longitudinal alignment with respect to the substantially straight portion thereof, the part of the bent portion of one of the legs of the bail being removable from the aperture of the flange through which it extends to permit the bail to be rotated about the aperture-received part of the bent portion of the other bail leg to move the bail to a displaced position for application of a wire to the wire-receiving portion of the wire connector, said legs of said bail being crossed at a point immediately above a portion of said wire-receiving portion to retain a wire in the channel of said wire-receiving portion, and means for preventing removal of said aperture-received part of the bent portion of said other bail leg from the aperture of the flange by which it is received.

9. A wire connector comprising a wire-receiving portion of channel cross-sectional shape having a substantially straight portion disposed in longitudinal alignment with reference to the direction of extension of a wire connected by the wire connector, and provided with a spiral wiresnubbing portion wound spirally about an axis which is extended at an angle with respect to the direction of extension of said substantially straight portion, a flange formed on said wire-

receiving portion at a point adjacent to said substantially straight portion thereof, said flange having apertures formed therein, and a bail having legs provide with bent portions parts of which are extended through the apertures of said flange so as to normally connect said bail to said wire-receiving portion in substantial longitudinal alinement with respect to the substantially straight portion thereof, the part of the bent portion of one of the legs of the bail being removable from the aperture of the flange through which it extends to permit the bail to be rotated about the aperture-received part of the bent por-

tion of the other bail leg to move the bail to a displaced position for application of a wire to the wire-receiving portion of the wire connector, said legs of said bail being crossed at a point immediately above a portion of said wire-receiving portion to retain a wire in the channel of said wire-receiving portion, and means comprising a bent end portion for preventing removal of said aperture-received part of the bent portion of said other bail leg from the aperture of the flange by which it is received.

OSCAR F. TALLMAN.
